[57] CLAIM

The ornamental design for a metal decking, as shown and described.

DESCRIPTION

FIG. 1 is a perspective view of a metal decking showing my new design, the decking is broken in the center to indicate indeterminate length;

FIG. 2 is a cross-sectional view taken along line 2—2 of FIG. 1;

FIG. 3 is a cross-sectional view taken along line 3—3 of FIG. 1;

FIG. 4 is a fragmentary side elevational view thereof;

FIG. 5 is a perspective view of a second embodiment of a metal decking showing my new design, the decking is broken in the center to indicate indeterminate length;

FIG. 6 is a cross-sectional view taken along line 6—6 of FIG. 5;

FIG. 7 is a cross-sectional view taken along line 7—7 of FIG. 5; and,

FIG. 8 is a fragmentary side elevational view thereof.

FIG. 1

FIG. 2

FIG. 3

FIG. 4

FIG. 8

FIG. 5

FIG. 6

FIG. 7
